(57) **CLAIM**

The ornamental design for a desk-mountable occupancy sensor, as shown and described.

DESCRIPTION

FIG. 1 is a front-top perspective view of a desk-mountable occupancy sensor.

FIG. 2 is a back-bottom perspective view of a desk-mountable occupancy sensor.

FIG. 3 is a front-side view of a desk-mountable occupancy sensor.

FIG. 4 is a back-side view of a desk-mountable occupancy sensor.

FIG. 5 is a left-side view of a desk-mountable occupancy sensor.

FIG. 6 is a right-side view of a desk-mountable occupancy sensor.

FIG. 7 is a top-side view of a desk-mountable occupancy sensor; and,

FIG. 8 is a bottom-side view of a desk-mountable occupancy sensor.

The broken lines in the drawings illustrate portions of a desk-mountable occupancy sensor that form no part of the claimed design.

1 Claim, 6 Drawing Sheets
